His Attorney.

UNITED STATES PATENT OFFICE.

RALPH I. FROST, OF AUGUSTA, KANSAS, ASSIGNOR TO THE GEO. W. BROWN & SON STATE BANK, TRUSTEE, OF AUGUSTA, KANSAS.

VALVE MECHANISM.

1,411,717.

Specification of Letters Patent.

Patented Apr. 4, 1922.

Application filed December 6, 1920. Serial No. 428,704.

To all whom it may concern:

Be it known that I, RALPH I. FROST, a citizen of the United States, residing at Augusta, in the county of Butler and State of 5 Kansas, have invented a certain new and useful Improvement in Valve Mechanisms, of which the following is a specification.

My invention relates to improvements in valve mechanisms.

10 The object of my invention is to provide a novel valve mechanism which is simple in construction, cheap to make, which may be readily assembled and dis-assembled, which will be easily opened and closed irrespective of the pressure to which it is subjected, and which is not liable to be clogged.

My invention provides further novel means for preventing iron rust and boiler scale from entering the valve casing and for the 20 removal of such rust, dirt or scale as may be thus arrested.

The novel features of my invention are hereinafter fully described and claimed.

In the accompanying drawing, which illustrates the preferred embodiment of my 25 invention,

Fig. 1 is a vertical sectional view of my improved valve mechanism, taken on the line 1—1 of Fig. 3.

30 Fig. 2 is a vertical sectional view on the line 2—2 of Fig. 3.

Fig. 3 is a horizontal section on the line 3—3 of Fig. 2.

35 Fig. 4 is a cross section on the line 4—4 of Fig. 2.

1 designates the body of a valve casing 40 provided with a vertical passage 2, which is, preferably, of cylindrical form and which intersects and is encircled by a port 3 with which a lateral intake passage 4 is provided.

The body 1 is provided with a chamber 5 which communicates with the upper end of the passage 2 and which at its upper end is provided with a threaded opening 6 which 45 is in alinement with the passage 2, and in which is fitted a removable closure comprising a screw plug 7.

50 Slidably fitted in the passage 2 and arranged to open and close the port 3 is a cylindrical valve 8, which is provided with a longitudinal opening 9 which communicates at its lower end with the passage 2 and at its upper end with the chamber 5. Equal areas at opposite ends of the valve 8

are exposed to fluid pressure in the passage 55 2 and chamber 5, thus affording a balanced valve.

Encircling the stem of the valve 8 in the chamber 5 is a coil spring 10, the upper end of which bears against the plug 7 and the lower end of which bears against a peripheral annular flange 11 on the stem of the valve 8. The tension of the spring 10 causes the valve 8 to close the port 3, as shown in Figs. 1 and 2. For opening the valve 8, 65 there is provided a rock shaft 12, which is oscillatably mounted in a horizontal central opening which extends through a screw plug 13 removably fitted in a lateral threaded hole 14 in the body 1 and which communicates with the chamber 5. A stuffing collar 15 encircles the rock shaft 12, is fitted in a threaded hole in the outer end of the plug 13, and bears against packing 16 in said plug encircling the rock shaft 12. The rock shaft 70 12 is provided with a crank comprising a sleeve 17 mounted on the rock shaft 12 in the chamber 5 and held from turning on the rock shaft by a removable pin 18. The sleeve 17 is provided with two lateral arms 80 19 which are disposed at opposite sides of the stem of the valve 8 and which are adapted to bear against the under side of the flange 11. The valve 8 is lifted to the open position against the pressure of the spring 85 10, when the rock shaft 12 is rocked in the proper direction by any suitable means, as by a crank 20 on the outer end of the rock shaft, the crank 20 having pivoted to it an operating member 21.

The lower end of the body 1 may be threaded and fitted into a threaded hole in a conductor 22 to which steam or other fluid under pressure is to be supplied from the intake passage 4. In and extending across 95 the passage 4 is a screen 23, Fig. 2, which is held between two rings 24 and 25, the ring 25 being fitted in the body 1. The rings 24 and 25 and the screen 23 are held in place by means of an internally threaded collar 100 26 across the central passage of which extends the screen 23. The collar 26 is removably attached to the body 1 in any desired manner, as by screws 27.

The collar 26 in its lower side is provided 105 with a threaded clean out hole 28, which communicates with the central passage of the collar and which has removably mount-

ed in it a screw plug 29. Interposed between the body 1 and collar 26 is a gasket 30.

In the operation of the invention, fluid under pressure is supplied to the passage 2 through the collar 26, passage 4 and port 3, when the valve 8 is lifted by the arms 19 to a position in which the port 3 will be open to the discharge end of the passage 2. The 10 fluid entering the passage 2 from the port 3 will be discharged into the conductor 22. Fluid will pass through the opening 9 into the chamber 5, thereby affording a pressure at the top of the valve 8 corresponding to the 15 pressure against the lower end of the valve.

The screen 23 will prevent iron rust, scale and large particles entering the passage 2, so that the valve 8 will not become clogged. By removing the plug 29, the collar 26 may 20 be cleaned.

The valve 8 may be readily removed, if desired, by withdrawing the plug 7, after which the pin 18 may be removed, so that the rock shaft 12 may be slipped out of the 25 sleeve 17. The valve 8 may then be withdrawn through the opening 6.

I do not limit my invention to the structure shown and described, as modifications, within the scope of the appended claims, 30 may be made without departing from the spirit of my invention.

What I claim is:—

1. In a valve mechanism, a valve casing having a passage and a chamber communicating with one end of the passage and having an opening in alinement with the passage, the casing having a port intersected by said passage, a valve slidably fitted in said passage and arranged to open and close said

port and having a longitudinal opening communicating with the passage and with said chamber, a closure for the opening of said chamber, a spring bearing against the closure and said valve for closing the latter, and means extending into said chamber for moving the valve to the open position against the pressure of said spring, substantially as set forth. 40

2. In a valve mechanism, a valve casing having a chamber and a passage communicating with the chamber, and provided with a port through which the passage extends, the chamber having an opening in alinement with said passage, a closure for the last named opening, a valve slidably fitted in said passage and arranged to open and close said port, a spring bearing against said closure and said valve for closing the latter, and a rock shaft extending into said chamber and having means for engaging and opening the valve against the pressure of said spring, substantially as set forth. 50

3. In a valve mechanism, a valve casing having a chamber, a passage communicating with the chamber, and a port encircling the passage, a valve slidably fitted in said passage and arranged to open and close said port and having a longitudinal opening communicating with said passage and with said chamber, opposite ends of the valve being provided with equal areas exposed to fluid pressure in the passage and chamber respectively, and means in said chamber for opening and closing said valve, substantially as set forth. 60

In testimony whereof I have signed my name to this specification.

RALPH I. FROST. 75
